UNITED STATES PATENT OFFICE

ELLISON EDWARD WORKMAN, OF MONTREAL, QUEBEC, CANADA, ASSIGNOR TO HIMSELF AND EDWARD ARTHUR ROBINSON, OF MONTREAL, CANADA

TERMINAL TUBE ADJUSTMENT FOR TRAIN CONNECTERS

Application filed September 19, 1922. Serial No. 589,145.

My invention relates to train pipe connectors and more specifically relates to improved means for limiting the forward position of the train pipe terminals within the head and to improved means for train support of the connector.

The main purpose of my invention is to provide a connector that is at once adapted to easy and inexpensive manufacture and to adequately meeting the needs of service.

10 A further purpose is to provide an adjustable clamp stop for limiting the forward position of the terminals within the head.

15 A further purpose is to provide reliable interlocking connections between the interior surface of the stop and the outer surface of the terminal about which it fits.

20 A further purpose is to provide the end of the bracket with lateral pivot projections and with a rearwardly extending eye, with which cooperate hook structure supporting the head and a buffer spring and retaining bolt for pressing the head forward.

25 Further purposes will appear in the specification and in the claim.

I have preferred to illustrate my invention by forms which are practical and effective but which have been selected primarily because they well illustrate the principles of 30 my invention.

In the drawings Figure 1 shows in side elevation a connector provided with my invention.

Figure 2 is a section illustrating one form 35 of my invention.

Figure 3 is a section through line 3—3 of Figure 2.

Figure 4 is a section similar to Figure 3 but showing a modified form.

40 Figure 5 is an enlarged section through line 5—5 of Figure 1.

Figure 6 is an enlarged section through line 6—6 of Figure 1.

Figure 7 is a broken perspective view showing the lower portion of the bracket.

45 In all the drawings like numbers refer to like parts.

Describing my invention in illustration and not in limitation and referring to the 50 drawings:—

The main features of my invention are embodied in the forward stop to limit the forward position of the train pipe terminals and in the connection between the bracket, the spring and the supporting arms for the head.

55 The improved stop is best illustrated in Figures 2—4 inclusive and I will describe this feature first.

The head 15 of the connector is provided 60 with openings 16 for the train pipe terminals 17 carrying gaskets 18. The head is inwardly flanged near the rear of the openings, at 19, and the terminal is enlarged at its outer end 20. A spring 21 surrounding the terminal between the enlargement and the flange presses the terminal outwardly in order that the gasket 18 may make tight connection with its mating gasket upon another head. The forward position of the terminal is limited 70 by the stop 22 coming against the flange 19.

In practice this stop is adjusted somewhat longitudinally along the terminal as the gasket wears away. It is also desirable that the stop shall take up as little as may be of the 75 length of the terminal.

In Figure 2, the terminal is shown with a threaded portion 23 at its outer end for screw connection to a fitting, and a portion 24 having a succession of devices which are 80 adapted for interlocking, shown in the form of grooves and flanges adapted to mate with corresponding flanges and grooves within the stop. These grooves and flanges may even be a continuous thread or, preferably, a succession of separate circumferential grooves and flanges each complete in itself. In either event the engaging faces of the interlocking portions upon the outside of the terminal and the inside of the stop are preferably substantially perpendicular to the terminal (radial) 85 in order that pressure upon the stop against the head in a direction axial to the terminal may have no tendency toward spreading the clamp.

If the flanges and grooves are individual, that is do not form a continuous thread, they are made relatively small and close together, adjustments in the position of the stop being in steps equal to the distance between suc- 90 95 100

cessive flanges. An advantage of this form of interlocking is that the stop may not possibly work loose by unscrewing along the terminal.

5 If the interlocking flanges and grooves are interlocking threads, the clamp serves substantially as a lock-nut, since it can be made to fit very tightly, is adapted to exact setting in any desired position and longitudinally 10 of the terminal takes up less space than a lock-nut. Another advantage as compared to the lock-nut stop is the avoidance of stress and wear upon individual threads, there being practically no tendency to wear out the 15 threads, which is by no means true with lock-nuts.

In the modification of Figure 4, the outside of the terminal is provided with longitudinal grooves or slots spaced about the circumference 20 along the portion 24 of the terminal, which is threaded with a thread having preferably the same pitch and diameter as the thread 23.

The stop nut 22' is screwed to position and 25 locked in place by means of the set screw 26 adapted to lock in any one of the grooves or slots. This set screw is preferably provided with a spring washer 27 to avoid possibility of its working loose.

30 Adjustments in the position of the stop nut are in steps determined by the pitch of the thread and the number of grooves or slots, and these steps may be as small as desired by making the grooves or slots sufficiently close together and the pitch of the 35 thread sufficiently small.

It will be noted that in both forms the stop is self-contained in that it carries its own lock to prevent movement of the stop.

40 My improved connection between the bracket and the supporting arms is illustrated in Figures 1, 5, 6 and 7.

The lower portion of the bracket 28 is provided with lateral pivot projections 29 and a 45 rearwardly extending eye 30 intermediate of the projections and to the rear thereof.

The double forward yoke 31, cast integral with the supporting arms 32, hooks over and 50 slides and pivots on the upper and lower sides of both of the projections, and has a yoke portion 33 behind the bracket perforated to surround the eye. The lower rear face of the bracket around the eye is made flat at 34 to receive and position the corresponding 55 flat on the front face 35 of the yoke.

The tie link 36 hooks in the eye and carries a cap 37 held in place adjustably by the nut 38. The spiral spring 39 is compressed between this cap and the yoke of the supporting arms, pressing this yoke forward, and the mating of the forwardly directed face of the yoke and the rearwardly directed face of the bracket serves to position the head in its foremost position, that is, when the cars are 60 disconnected.

The cap 37 is forwardly flanged at 40 to position the outer end of the spring which is positioned at its inner end by the rearwardly extending flange 41 on the back of the yoke. 70

Preferably the projections and the eye are cast integral with the bracket but it is, of course, evident that any or all of them may be made separate and removable from the bracket.

In view of my invention, modifications and variations of my invention to meet individual whim or particular need will doubtless become evident to others skilled in the art and I claim all such modifications and variations in so far as they fall within the reasonable spirit and scope of my invention. 75

Having thus described my invention, what I claim as new and desire to secure by Letters Patent is:—

In an automatic train pipe connector, a 80 coupling head supported from fixed train parts in position for automatic coupling and having an opening therethrough, an inwardly projecting flange near the rear of the opening, a train pipe terminal passing through the opening and enlarged at its forward end to slide in the opening, a spring between the flange and the enlarged portion of the terminal forwardly pressing the terminal from the flange, a clamp stop about the terminal pipe to the rear of the flange to limit the forward position of the terminal and adapted for adjustment about the terminal pipe, and members free from axial advancement along the terminal adapted to interlock on the inside of the clamp and the outside of the terminal pipe. 85
